UNITED STATES PATENT OFFICE

2,371,950

HEATER

Thomas C. Cheasley, Kansas City, Mo.

Application June 21, 1941, Serial No. 399,113

8 Claims. (Cl. 126—77)

This invention relates to heaters of the magazine type and wherein fuel is caused to burn from the bottom to coke and distill gases from the fuel in the upper portion of the magazine. In heaters of this character it is difficult to supply an adequate amount of air to the upper portion of the magazine, and particularly the space over the top of the magazine, to effect combustion of the gases and any smoke that may arise directly from the fuel, since most of the air is utilized before it reaches the upper portion of the heater.

It is, therefore, a principal object of the present invention to provide a heater of this character wherein a supplementary supply of air is passed directly across the top of the magazine to effect more thorough burning of the products of combustion in the upper portion of the heater.

Other objects of the invention are to provide for preheating the supplementary air supply; to provide the heater with means for diverting the draft to retard discharge of the spent products of combustion, thereby obtaining a more efficient heater; and to provide a down-draft flue for the spent products of combustion located in heat exchange relation with the supplementary air supply.

It is also an object of the invention to provide a simple and relatively inexpensive structure for directing the secondary air supply.

In accomplishing these and other objects of the invention, as hereinafter pointed out, I have provided improved structure, the preferred form of which is illustrated in the accompanying drawings, wherein:

Fig. 1 is a perspective view of a heater embodying the features of the present invention, outer portions thereof being broken away to better illustrate the interior construction.

Fig. 2 is a vertical section through one side of the heater.

Fig. 3 is a detail sectional perspective view of the shutter for controlling the air supply used in effecting combustion of the evolved gases.

Fig. 4 is a vertical section through the heater on the line 4—4 of Fig. 2.

Fig. 5 is a detail perspective view of one of the refractory flues.

Fig. 6 is a perspective view of the refractory forming the supplementary air supply and down-draft ducts.

Fig. 7 is a perspective view of the hood or baffle for directing the supplementary air supply and controlling directional movement of the burning gases in the upper portion of the heater.

Fig. 8 is a cross-section through the heater on the line 8—8 of Fig. 4.

Fig. 9 is a similar section on the line 9—9 of Fig. 4.

Fig. 10 is a fragmentary horizontal section on the line 10—10 of Fig. 4.

Fig. 11 is a detail perspective view of the lower flue connection.

Referring more in detail to the drawings:

1 designates a heater constructed in accordance with the present invention, and which includes a base 2 supported from the floor by legs 3 and having a top 4 forming the bottom of an ash compartment 5. Carried on the base is a jacket or casing 6 formed of sheet metal and closed at the upper end by a top 7. The top 7 has a door opening 8 at the front thereof, closed by a door 9 through which a magazine 10 is charged with fuel.

Supported by the casing, and forming the top of the ash compartment, is a grate assembly 11 including an outer ring section 12 having a notched inner periphery to form a plurality of air passageways 13 circumferentially of an inner grate section 14 having openings 15 cooperating with the passageways 13 for passing primary air directly through the magazine for promoting burning of the choke, as later described. The inner grate section has a central opening 16 across which is slidably mounted a shaker plate 17. The shaker plate is manipulated by a forwardly extending arm 18, having an apertured end 19 adapted to be engaged by a poker or the like for reciprocating the plate to discharge ashes from the magazine into the compartment 5.

Formed at opposite diametrical sides of the ring 12 are substantially arcuate slots 20 for passing air to refractory flues 21 and 22, later described. Flow of air through the slots 20 is controlled by substantially arcuate shaped shutters 23 slidably supported by guide lugs 24 below the under face of the ring 12, the shutters 23 being provided with arcuate openings 25 adapted to register with the slots 20 when in full open position. The shutters are manipulated by levers 26 having exterior handle portions 27 operable through slots 28 of the casing.

The heater casing is provided adjacent each of the refractory flues with an arcuate liner 29 extending from the grate assembly 11 to the upper portion of the casing for protecting the relatively thin metal casing from the heat of the gas burning in the refractory flues. The intermediate lower part of the casing is lined with refractory elements 30 having ends 31 provided with flanges 32 overlapping the side edges of the liners 29. The refractory elements 30 may be formed of one or more sections with the adjacent edges of the sections provided with ship-lap

joints as indicated at 33 in Fig. 9. Supported on the refractory elements 30 are upper refractory elements 34 of similar design but preferably formed of thinner material so as to provide a more ready transfer of heat through the casing of the heater. The refractory elements 30 at the back of the heater are shown of greater length than the front elements so that they substantially correspond in length to that of a supplementary air and down-draft member 35, later described.

The refractory flues 21 and 22 are best illustrated in Fig. 5 and each includes a substantially flat body portion 36, having vertically spaced lugs 37 and 38 projecting from the respective sides thereof to form a series of spaces 29 for the inlet of gases into the flue, which are evolved from the fuel as later described. The lugs also project from the inner faces of the flues to space the body portions thereof from the liners 29 and form vertical passageways 40 extending from the grate ring to a point below the top of the heater casing. The side portions of the flues, below the spacing lugs, have flanges 41 and 42 to abut against the liners 29.

The upper ends of the refractory flues are cut away, as at 43, to cooperate with the member 35 in forming inclined seats to support a baffle plate 44. The member 35 is also formed of refractory material and includes a channel-shaped body portion 45, having side flanges 46 and 47 engaging the rear refractory elements 30 and cooperating therewith in forming a down-draft passageway 48. Formed on the front of the channel-like body, and preferably integrally therewith, is a coextensive vertically arranged air duct 49 terminating under the baffle 44. The upper ends of the flanges 46 and 47 are also cut away to accommodate the slope of the baffle 44. The baffle 44 includes a substantially semicircular plate-like body 50, having a notch-like opening 51 registering with the down-draft passageway 48 and provided across the front side with an upwardly and rearwardly extending flange 52, as best shown in Figs. 4 and 7, the flange 52 being located below the rear upper edge of the door opening to direct the fuel into the magazine and prevent piling thereof on top of the baffle. All of the refractories just described are supported upon the outer ring section 12 of the grate, but a portion of the lower end of the member 35 extends through the grate to connect directly with the ash compartment 5. In order to deliver the heated air passing through the duct 49 over the bed of solid fuel and to form a better mixture with the gases evolved, the baffle 44 has a duct 49' on the under side of the plate-like body 50 which connects with the duct 49 and discharges the heated air into the combustion chamber 65.

Supported in the ash compartment, and having shouldered connection with the lower end of the member 35, is a refractory flue connection 53 forming a continuation of the passageway 48 and having an outlet opening 54 connected with an opening 55 formed in the lower end of the heater casing. Connected with the exterior of the casing, in registering relation with the opening 55, is an elbow 56 that is provided with a clean-out door 57. The elbow is turned so that the outlet 58 extends upwardly and connects by a pipe 59 with a tee 60, which in turn is connected to the smoke pipe 61 adapted to connect with a chimney (not shown). The branch 62 of the tee connects with a flue connection 63

formed in the heater top 1, the opening of the flue connection 63 being controlled by a damper 64 so that when the opening is closed by the damper, the spent products of combustion will be diverted downwardly through the passageway 48 for discharge through the lower flue connection 53 to the pipe 61. The front of the ash compartment has an opening 65 closed by a door 66 provided with the usual draft control damper 67, wherethrough air is admitted to the ash compartment for effecting combustion of the fuel.

In using a heater constructed and assembled as described, a fire is kindled on the grate and a sufficient amount of fuel is charged in the magazine through the door opening 8 so as to form a good bed of coals. When the fire is first started, the damper 64 is opened to provide maximum draft through the heater to heat the refractory ducts 48 and 49, and chimney. The magazine is then filled with fuel substantially to the top of the supplementary air supply duct 49. The damper 64 is then closed to divert the products of combustion through the duct 48 and maintain the required temperature of the air duct 49. As the fire burns, the fuel is converted into coke which is consumed in the lower portion of the magazine, and the ashes are discharged into the ash compartment. The gases evolved incidental to coking of the fuel pass through the openings 30 into the flue passageway 48, wherein the gas burns upon contact with the air, forming a combustible mixture, the supply of air being regulated by adjustment of the shutters 23 so as to maintain proper combustion. Smoke and a portion of the gases, particularly those evolved in the upper portion of the magazine, pass upwardly over the baffle and are discharged through the upper or lower flue connections, depending upon the position of the damper 64. Ordinarily the smoke and gases in the upper part are not provided with an adequate supply of air, so that they are discharged unburned from the heater. However, with the present construction, a supplementary supply of air is delivered to the under side of the baffle by way of the duct 49 and is directed by the duct 49' into contact with the smoke and gases in an upper combustion chamber 65 so that by the time they pass over the baffle they are ignited and only spent products of combustion are discharged through the flue connections. In addition to preheating the supplementary air passing upwardly through the duct 49 in promoting burning of the gases, the down-draft provides a check in controlling the burning rate of the fuel. The primary air supporting burning of the fuel in the bottom of the magazine is supplied directly through the grate, as in conventional practice, the amount of air being diverted through the refractory flues and through the duct 49, depending upon the adjustment of the shutters 23, all of the air being controlled by the dampers 64 and 67 to regulate the burning rate of the fuel.

What I claim and desire to secure by Letters Patent is:

1. A heater including, a casing having an ash compartment and means for admitting air to the ash compartment, means forming a fuel magazine in the casing, a flue substantially coextensive with the side of the magazine and having connection with the ash compartment to supply combustion supporting air for gases evolved in the burning of fuel in the magazine and having an outlet above the magazine, a duct separate from the flue and extending from the ash compart-

ment to the upper portion of the magazine for supplying supplementary air to the upper portion of the magazine, means for selectively controlling flow of air through said flue, a baffle extending across the top of the magazine and below the outlet of said flue for retarding gases rising through the magazine for mixture with said supplementary air separately of gases discharged from said flue, and a down-draft flue associated with said duct for discharge of spent products of combustion from said heater.

2. A heater including, a casing having an ash compartment, a grate above the ash compartment, means for admitting air to the ash compartment, a fuel magazine supported above the grate, a flue substantially coextensive with the side of the magazine and having connection with the ash compartment to supply combustion supporting air and provide a combustion chamber for gases evolved in the burning of fuel in the magazine, a duct separate from the flue and extending through the grate from the ash compartment to the upper portion of the magazine for supplying supplementary air, a baffle intermediate discharge outlets of said flue and duct, means for selectively controlling flow of air through said flue, and a down-draft flue associated with said duct for discharge of spent products of combustion from said heater.

3. A heater including, a casing having upper and lower flue connections, an ash compartment in the casing, means for admitting air to the ash compartment, means forming a fuel magazine in the casing, a flue substantially coextensive with the side of the magazine and having connection with the ash compartment to supply combustion supporting air and provide a combustion chamber for gases evolved in the burning of fuel in the magazine, a duct separate from the flue and extending from the ash compartment to the upper portion of the magazine for supplying supplementary air, means for selectively controlling flow of air through said flue, a down-draft flue associated with said duct and connected with the lower flue connection, a baffle extending across the magazine on the side adjacent the down-draft flue and separating discharge outlets of said first-named flue and duct to effect combustion of gases rising directly from the top of the magazine prior to admixture with spent products of combustion discharged from the first-named flue, and means for selectively directing spent products of combustion through said flue connections.

4. A heater including, a casing, means forming a fuel magazine in the casing, a baffle covering a portion of the top of said magazine for controlling directional movement of gases issuing from the magazine, duct means extending vertically of the magazine for supplying combustion supporting air and providing a combustion chamber, said duct having openings from the magazine into the combustion chamber of said duct for passing gases evolved in burning of fuel in the lower portion of the magazine and having an outlet substantially at the top of the magazine for discharging spent products of combustion from the combustion chamber, and a duct having imperforate walls substantially coextensive with the magazine and having a discharge opening under said baffle for supplying supplementary air for mixture with any gases rising directly through the magazine.

5. A heater including, a casing having an ash

compartment and means for admitting air to the ash compartment, means forming a fuel magazine in the casing, a flue located within the magazine at one side thereof and having connection with the ash compartment to supply combustion supporting air and provide a combustion chamber said flue having openings for admitting gases into said flue which are evolved in the burning of the fuel in the lower portion of the magazine and having an outlet into an upper combustion chamber above the magazine, a duct separate from the flue and extending from the ash compartment to the upper portion of the magazine for supplying supplementary air, a baffle extending transversely across the magazine and separating said upper portion of the magazine from the upper combustion chamber, and means for selectively controlling flow of air through said flue.

20 6. A heater including, a casing, a grate in the casing, means supported above the grate to form a fuel magazine in the casing, an upwardly and inwardly sloping baffle covering a portion of the top of said magazine for controlling directional movement of the gases rising directly through said magazine, a flue extending vertically of the magazine and connected with an air supply space below the grate for supplying combustion supporting air from a point below the grate and having a series of vertically arranged openings for the admission of gases evolved in the upper portion of the magazine and having an outlet substantially at the top of the magazine, and a duct located within the magazine and extending through the grate and having a discharge opening under said baffle for supplying supplementary air for mixture with the first named gases independently of gases discharged from the outlet of said flue.

30 7. A heater including, a casing, means forming a fuel magazine in the casing, combustion and air supply flues at opposite sides of the magazine for supplying combustion supporting air and providing a chamber for combustion of gases evolved in burning of fuel in the lower portion of the magazine, said flues having openings to pass the gases from the magazine into the combustion chambers of said flues, a baffle supported at the upper ends of said flues for controlling directional movement of any gases that may discharge from the top of said magazine, and a down-draft duct extending downwardly of the magazine from said baffle for discharging spent products of combustion.

40 8. A heater including, a casing, means forming a fuel magazine in the casing, a baffle covering a portion of the top of said magazine for building up temperature and controlling directional movement of gases issuing from said magazine, duct means extending vertically of the magazine and connected with an air supply space below the magazine for supplying combustion supporting air and providing a combustion chamber, said duct means having gas inlet openings in a side thereof for gases evolved in burning of fuel in the lower portion of the magazine and having an outlet at the top of the magazine for discharging spent products of combustion, and a duct having imperforate walls extending upwardly within the magazine and having a discharge outlet below the baffle for discharging supplementary air under said baffle to effect combustion of gases rising to the top of the magazine.

THOMAS C. CHEASLEY.
